UNITED STATES PATENT OFFICE.

WILLIAM H. DELANEY, OF PEORIA, ILLINOIS.

STORE-CABINET.

1,253,356.

Specification of Letters Patent. Patented Jan. 15, 1918.

Application filed December 14, 1914. Serial No. 877,264.

To all whom it may concern:

Be it known that I, WILLIAM H. DELANEY, citizen of the United States, residing at Peoria, in the county of Peoria and State of Illinois, have invented certain new and useful Improvements in Store-Cabinets; and I do hereby declare that the following is a full, clear, and exact description of the invention, which will enable others skilled in the art to which it appertains to make and use the same.

This invention relates to store cabinets. It pertains more particularly to a cabinet in which to display and from which to sell articles of food. It is particularly adapted for the display of articles of sale, the cabinet being so constructed that it can be opened fully at two of its sides when a sale is to be made.

20 An object of the invention is to provide a sanitary cabinet whose top and one of its walls may be opened and moved out of the way to permit working within the cabinet by the use of a very simple form and mechanism.

Another object is to furnish a cabinet of simple construction the top and one side of which can be opened and closed and that will operate smoothly and with the least 30 amount of effort and which will balance one another without requiring separate balancing parts.

Another object is to furnish a cabinet wherein none of the movable parts will extend laterally from it in the way of persons working about or passing said cabinet.

Other objects of the invention will appear herein aided by the accompanying drawing, in which,

40 Figure 1 shows the cabinet in perspective.

Fig. 2 is a side elevation of the cabinet in section.

Fig. 3 is a horizontal section of two parts of the cabinet, one being slidable in the 45 other; and,

Fig. 4 is a sectional elevation of parts of the cabinet showing the relative positions of its bottom and a sliding closure when the latter is opened to its widest limit.

50 A A indicate the sides of the cabinet, B the front, and C the bottom. Preferably the sides and front are furnished with transparent panels A' through which the customer may view the goods on sale.

55 D is a closure for the rear side of the cabinet arranged in an upright position and

slidable in grooves E on the inside surfaces of the sides A, there being but one of said grooves shown in the figures.

The top of the cabinet is represented at 60 F being hinged to the front portion as at G, for example. H H represent two hangers pivotally suspended at their upper ends from the upper rail of each side A. A lever-arm J is pivoted between its ends to 65 the depending free end of each of said hangers. One end of each of said lever-arms is pivoted to a suitable bracket K secured to the sliding closure D, the opposite end being pivotally attached to one end of 70 a link L, the other end of the latter being pivoted to a suitable bracket M secured to the under side of the top F.

The brackets K are attached to the closure D near its upper edge so that in the lowest 75 position of said closure its upper edge d will lie substantially flush with the upper surface of the bottom C so that the said upper surface will be unobstructed, as a working surface as shown in Fig. 4, thus giving the attendant clear working space for the use of 80 a knife for instance which can be brought down squarely upon the said bottom when cutting articles of sale such as cheese, the closure being entirely out of the way.

85 The dotted lines indicate the various positions of the several parts of the structure when the closure D and the top F are closed or wide open, the full lines indicating substantially the middle position of these portions. The relation of these parts to one another is necessarily such that when the top is closed, the closure D must have been raised to its highest limit to meet it. Also, when the top is raised entirely out of the way, the 90 closure D must descend to the lowest position described. The weight of the top with respect to that of the closure D, together with the relation of the leverages of the members J must be such that the closure D and the 95 said top will balance one another.

Preferably the top F has a depending apron F' provided with a handle F². The apron and the top edge of the closure D are correspondingly rabbeted so that a dust-tight joint is formed. By reason of the fact, also, that the closure D lies in the grooves E, the interior of the cabinet is still further protected from dust and the entrance of insects.

100 It is observed that the upper edge of the closure D is recessed so as to leave the upwardly projecting corner portions D'. The

brackets K, which may rest upon the bottom C when the cabinet is open are attached to these corners leaving the intermediate portion flush with the bottom C as already explained.

There are certain cheese cabinets on the market more or less complicated in structure, all of which require considerable effort to operate on account of the structure employed and are otherwise unsatisfactory. However, the cabinet shown herein, operates smoothly and but little effort is required in the operation since the parts are nicely balanced and in addition the fact, also, that as the closure 15 D moves in vertically arranged guides little or no binding can result.

My structure differs from those of the art in that the top F moves upward and the vertically movable part D both move entirely 20 out of the way of the operator and expose the entire interior space which in a cheese cabinet, for example, is extremely important, the operator being enabled to work within said cabinet without being hampered in any 25 way, the said part D dropping so far down that its upper edge is at least flush with the upper surface of the bottom C.

A closure cannot be permitted to open toward the operator since he is compelled to 30 work at arms length and therefore at a disadvantage besides which when in cramped quarters such a form of device is very undesirable on account of the space necessary to provide for its use.

35 A cabinet having a top portion slideable parallel to the bottom cannot be fully opened and if so constructed as to be fully opened said top would be projected beyond the space allotted to the cabinet and these are all disadvantages recognized by the trade.

40 My device, however, has none of these disadvantages. Furthermore, as distinguished from the art the mechanism of my said device is exceedingly simple since there are 45 merely the opposite swinging hangers H to which the levers J are fulcrumed, and the arms L so arranged that the two closures balance one another, the said hangers swinging with the said lever J as that member 50 takes its longitudinal movement in following the member D.

I claim:—

1. In combination, a cabinet having a slideable closure for one of its sides, and a hinged 55 closure for one of its other sides, of a separate member pivotally attached to each closure one being pivotally connected to the other, and a pivotally suspended arm, one of the members being directly pivoted between 60 its ends thereto.

Copies of this patent may be obtained for five cents each, by addressing the "Commissioner of Patents, Washington, D. C."

2. The combination in a cabinet, of a bottom, two side walls and a third wall connecting the said side walls, a closure hinged at the top of the said third wall and adapted to close the top side of the cabinet, a closure 65 at the open side of the cabinet arranged to have movement in a plane parallel to the said third wall, a member carried by the cabinet and adapted to swing, a lever fulcrumed between its ends on said member, and having pivotal connection with the last named closure, and a member pivoted at one end to the opposite end of the lever and pivotally connected to the first named closure.

3. The combination with a cabinet open 75 at one side and at its top, of a closure for the open top of said cabinet hinged at one of its edges to one of the walls of said cabinet and having a depending portion, a closure for the open side adapted for movement 80 parallel to said open side and the wall opposite said open side, the upper edge of the last named closure adapted to abut against the depending portion of the first named closure, a link pivotally suspended from the 85 cabinet at each side and free to swing, a lever fulcrumed between its ends on each link and pivotally attached to the second described closure, and a member pivoted to the other end of each lever and pivotally attached to 90 the first described closure.

4. The combination with a cabinet open at one side and at its top, of a closure for the open top of said cabinet hinged at one of its edges to one of the walls of said cabinet, 95 a closure for the open side adapted for movement parallel to said open side and the wall opposite said open side, and engaging runways carried by the side walls, the upper edge of the last named closure when wide 100 open adapted to lie substantially flush with the upper surface of the bottom of the cabinet and having extensions adapted to project above said bottom, the extremity of the first named closure adapted to abut upon 105 the said upper edge of the other, a link pivotally suspended from the cabinet at each side and free to swing, a lever fulcrumed between its ends on each link and each pivotally attached at one end to the extensions 110 of the second described closure, and a member pivoted to the other end of each lever and pivotally attached to the first described closure.

In testimony whereof I affix my signature, 115 in presence of two witnesses.

WILLIAM H. DELANEY.
